UNITED STATES PATENT OFFICE.

HOUSTON MATTHEW WILLIS, OF PRAIRIEVILLE, ALABAMA.

ATTACHMENT FOR GUITARS.

No. 823,657.

Specification of Letters Patent.

Patented June 19, 1906.

Application filed November 20, 1905. Serial No. 288,189.

To all whom it may concern:

Be it known that I, HOUSTON MATTHEW WILLIS, a citizen of the United States, residing at Prairievile, in the county of Hale and State of Alabama, have invented new and useful Improvements in Attachments for Guitars, of which the following is a specification.

My invention is an attachment for guitars to prevent injury to the sounding-board and also to provide a support for the right hand of the player.

In the accompanying drawings, Figure 1 is a plan view of a guitar, showing the attachment applied. Fig. 2 is a perspective view of the attachment removed.

Referring specifically to the drawings, 5 denotes the body of a guitar; 6, the sounding-board, having the usual sound-hole 7; 8, the neck; 9, the bridge, and 10 the strings.

The attachment comprises a thin strip 11 of suitable metal extending lengthwise over the sounding-board from the bridge to the neck. The end of the strip adjacent the bridge is formed with an ear 12, having a perforation 13 for a screw 14, whereby it is fastened to the bridge. The opposite end of the strip is formed with a perforated ear 15 for attachment to the neck of the instrument. The inner longitudinal edge of the strip is cut away, as at 16, to register with the sound-hole, and its opposite or outer edge is formed with an upwardly and inwardly curved flange 17.

The strings of the instrument are picked by the right hand, the latter being usually supported by placing the little finger on the sounding-board. The continued use of the instrument results in wear and damage of the sounding-board by reason of the contact of the finger-nail therewith. This trouble is entirely avoided by the use of the attachment, which serves as a wear-plate and effectively shields the sounding-board from the contact of the finger-nail therewith. The flange 17 at the outer edge of the strip prevents the little finger from slipping, which materially aids in sustaining the hand in proper position to pick the strings. The adjustment can be readily secured to the instrument without danger of injury thereto.

Having thus described my invention, what is claimed as new, and desired to be secured by Letters Patent, is—

The combination with a guitar, of a strip secured to the sounding-board and extending from the bridge to the neck, the outer longitudinal edge of the strip being formed with an upturned flange.

In testimony whereof I have signed my name to this specification in the presence of two subscribing witnesses.

HOUSTON MATTHEW WILLIS.
